(57) **CLAIM**

I claim the novel design for an in-vehicle TV receiver and audio disc player, as shown.

DESCRIPTION

FIG. 1 is a top, front, and right side perspective view of my new design for an in-vehicle TV receiver and audio disc player with the TV screen in the closed position;

FIG. 2 is a top, front, and right side perspective view of my new design for an in-vehicle TV receiver and audio disc player with the TV screen in the open position;

FIG. 3 is a top, front, and right side perspective view of my new design for an in-vehicle TV receiver and audio disc player with the TV screen in the closed position and the control panel disconnected;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a left side elevation view thereof showing the TV screen horizontally withdrawn from its storage compartment;

FIG. 11 is a left side elevation view thereof showing the TV screen partially elevated;

FIG. 12 is a left side elevation view thereof showing the TV screen vertically positioned;

FIG. 13 is a front view thereof showing the TV screen vertically positioned; and,

FIG. 14 is a rear view thereof showing the TV screen vertically positioned.
